UNITED STATES PATENT OFFICE.

CHARLES C. WINTER, OF PITTSBURGH, PENNSYLVANIA.

RULE-HOLDER.

1,321,175.

Specification of Letters Patent.

Patented Nov. 11, 1919.

Application filed February 13, 1918. Serial No. 216,884.

To all whom it may concern:

Be it known that I, CHARLES C. WINTER, a citizen of the United States, residing at Carrick, Pittsburgh, in the county of Allegheny and State of Pennsylvania, have invented certain new and useful Improvements in Rule-Holders, of which the following is a specification.

This invention relates to rule holders and 10 has for its object the production of a simple and efficient spring clasp which may be adjustably supported upon a portion of the foldable rule for facilitating the holding of the foldable rule within a pocket.

15 Another object of this invention is the production of a simple and efficient means for attaching the spring clasp to the ruler.

With these and other objects in view, this invention consists of certain novel constructions, combinations and arrangements 20 of parts as will be hereinafter fully described and claimed.

In the drawings:

25 Figure 1 is an edge elevation of the rule in a folded position showing the ruler holder carried thereby,

Fig. 2 is a side elevation of a portion of the ruler showing the ruler holder supported thereon,

30 Fig. 3 is a perspective view of the ruler holder clasp,

Fig. 4 is a section taken on line 4—4 of Fig. 2, looking in the direction of the arrow.

35 By referring to the drawings, it will be seen that 1 designates the ruler which may be of the usual or ordinary construction of the folding type and the ruler holder is adjustably secured to one of the sections 40 of the ruler 1 as shown in Fig. 2 of the drawing. This ruler holder comprises a clamp 2 which clamp 2 is adapted to fit around one of the sections of the ruler and is provided with a pair of laterally extending

45 side flanges 3, these side flanges fitting snugly in engagement with each other as shown in Fig. 4. Suitable securing bolts 4, extend through these flanges 3 and carry nuts 5 for firmly clamping the jaws 5 of the clamp 2 in engagement with the ruler 1.

50 This clamp 2 is preferably rectangular in shape so as to fit snugly around the section

of the ruler and permit the clamp 2 to be adjustably supported upon the section of the ruler in any suitable or desired position. 55

A spring clamping tongue 7 is secured to the front edge 8 of the clamp 2, having its upper end secured thereto by means of suitable rivets 9. This spring tongue 7 constitutes a gripping clasp and is provided 60 with an outwardly bent shank 10 terminating in a depending spring tongue 11, this tongue being slightly curved outwardly at its lower end and being provided with an upwardly inclined lip 12 at the lower end 65 thereof.

In operation, the ruler is folded as shown in Fig. 1 and the same is placed in the pocket of a workman and the spring clasp or tongue 7 is extended over the outer face 70 of the pocket, the spring nature of the tongue or clasp 7 firmly gripping the outer face of the pocket and holding the ruler against accidentally falling from the pocket of the workman. At the same time the ruler 75 may be easily removed from the pocket by pulling upwardly upon the same, but the spring clasp or tongue 7 will possess sufficient resiliency to firmly hold the ruler against accidentally dropping from the 80 pocket. Furthermore due to the construction of the lower end of the clasp or tongue 7, the ruler may be easily placed in the pocket and the spring tongue 7 will automatically slide upon the outer face of the 85 pocket and firmly hold the ruler in a proper position. The up-turned lip 12 will prevent the spring clasp 7 from catching in the pocket while the ruler is being inserted and will guide the spring tongue 7 over the outer 90 face of the pocket to a proper clamping position.

What is claimed is:

As a new article of manufacture, a rule holder comprising a clamp formed of sheet 95 metal adapted to fit snugly around a section of a rule and having laterally extending flange portions adapted to fit snugly together for receiving a clamping means, a spring clasp secured to the front edge of 100 said clamp and adapted to lie snugly against the edge of a ruler, said clamp provided with an outwardly bent shank terminating in a gradually inwardly extend-

ing curved lower end, the extremity of said curved lower end being outwardly bowed and terminating in a gripping lip bent outwardly at an angle from said lower end, the lower end of said clasp adapted to snugly

supporting medium for firmly supporting the ruler carried thereby within a pocket. 10
In testimony whereof I affix my signature in presence of two witnesses.

CHARLES C. WINTER.
